INTERLOCKING SYSTEM FOR RAILROADS

Andrew Langdon, Brighton, and George H. Wien,
Rochester, N. Y., assignors to General Railway
Signal Company, Rochester, N. Y.

Application June 28, 1933, Serial No. 678,042

11 Claims. (Cl. 246—135)

This invention relates to interlocking systems for railroads, and more particularly pertains to the remote control of railroad track switches employed in such systems.

5 In one type of control system for railroad track switches, the positions of the levers in the tower are repeated at their respective switch machines so as to control the operating power local to the track switches. The positions of the track switches, thus controlled, are then indicated in the tower, or control office, by suitably controlling the usual switch position repeating relays over polarized circuits. This general arrangement of control and indication has been employed both 10 where the levers of the interlocking plant have been of the usual four-position mechanically interlocked type, and where the levers have been of the two-position "free lever" type.

In both cases, one problem has been to insure 20 that the track switches are always in correspondence when not in operation, with their respective control levers and to particularly provide that the control levers can not be juggled out of correspondence with their track switches 25 when the four-position type of mechanical interlocked lever is employed.

The present invention provides for the control and indication of track switches in a manner which is so organized and interrelated that the 30 switch position indicating relay for each track switch always indicates the actual position of the track switch, as well as its anticipated operation upon the movement of its control lever to a new governing position. In other words, a 35 system of control wherein the position of the track switch is indicated by the energization of a relay over a polarized circuit has been open to the objection that a new lever movement initiates a switch machine operation prior to the indication of the unlocked condition of the track 40 switch in the tower. However, the present invention eliminates such a condition by positively providing that the switch machine may not operate until an indication of its unlocked condition is given in the tower, or at the point at 45 which power is applied.

Various other features of the present invention reside in the novel circuit arrangements wherein the desired degree of inherent cross protection 50 and safety is provided.

Other objects, purposes and characteristic features of the present invention will be in part obvious from the accompanying drawings and in part pointed out as the description of the invention progresses.

In describing the invention in detail, reference will be made to the accompanying drawings in which like reference characters designate corresponding parts throughout the several views and in which:

Fig. 1 illustrates one embodiment of the present invention as applied to a remote control type of installation having mechanically interlocked switch machine control levers in the tower;

Fig. 1A illustrates a modified form of Fig. 1, 10 wherein free levers may be employed in the tower by the provision of electric locking.

While certain features of the invention are applicable to, and usable with any type of traffic controlling system, the invention has been illustrated as embodied in the type of remote control in which the control tower or office is comparatively local to the track layout, at least sufficiently so, as to warrant the use of direct line wire control as compared to the selector or code 15 type system of control. However, it is to be understood that the present invention may be adapted to a code type system of remote control, all within the scope of the invention as will be more particularly pointed out hereinafter. 25

Apparatus

With reference to Fig. 1 of the accompanying drawings, a track switch TS is indicated as being operated by a suitable switch machine 30 mechanism SM, which may be of any suitable type, such for example, as disclosed in the patent to W. K. Howe, Patent No. 1,466,903, dated September 4, 1923, but having the control for its operating motor arranged as provided in accordance with the present invention.

Associated with the track switch TS and the switch machine mechanism SM is a suitable point detector contact mechanism PD which may be of any suitable type, such for example, as disclosed in the patent to C. S. Bushnell, Patent No. 1,517,236 dated November 25, 1924. For the purpose of simplifying the present disclosure, this point detector contact mechanism has only been illustrated as having movable contacts 10, 11, 45 12, and 13, but it is to be understood that these contacts are jointly operated by the track switch TS and the switch machine SM so as to assume normal or reverse extreme positions when the track switch TS is operated to corresponding extreme positions and locked by its switch machine SM, and to assume intermediate mid-stroke positions whenever the track switch TS is in operation or is unlocked.

The switch machine mechanism includes an 55

operating motor having an armature A and a field winding F. This motor has its control circuits jointly governed by a control contactor C, a normal contactor NC and a reverse contactor RC. These contactors are in turn controlled by a switch machine lever SML located in the tower as well as being subject to an overload protective device OL. The contactors C, NC, RC and the overload protective device OL are preferably located in a suitable housing within the switch machine mechanism, although some other disposition of the apparatus might be made and still be within the contemplated use of the present invention.

The contactors C, NC, and RC are of the neutral electro-magnetic type and may have their contacts restored to normal deenergized positions by gravity or by some other biasing means. Their structures may be of any suitable design, but their general characteristics are preferably along the lines as disclosed, for example, in the pending application of J. F. Merkel, Ser. No. 552,906, filed July 24, 1931, now become U. S. Patent No. 2,002,476, granted May 21, 1935. Those contacts of these contactors which have heavy portions on the movable arm indicate that such contacts preferably have associated therewith suitable magnetic blow-out means to effect the suppression of arcs at such contacts.

The overload device OL is of the usual neutral relay type having contacts which are biased to normally deenergized positions by gravity or other suitable biasing means. This overload device is illustrated as having two windings 14 and 15 which are considered to be upon the same electromagnetic structure although the coils have been shown in spaced positions. The coil 14 is a stick winding; while the coil 15 is the operating winding which carries the operating current of the motor and actuates the contacts of this overload device OL to picked up or energized positions only when the operating current has risen above a predetermined value. Suitable means may be associated with this overload device for delaying its response to surges of current so that it will not trip or operate upon the initial closing of the motor operating circuits. Such means may be retarding short circuiting slugs, or may be special bucking coils, as shown, for example, in the patent to Hoppe and Swanton, Pat. No. 1,877,876 dated September 20, 1932, all of which is immaterial to an understanding of the features of the present invention although preferable in actual installations.

In the tower or control office is located a suitable interlocking machine having a switch control lever SML for governing the operation of the track switch TS. This lever SML operates movable contact members 16, 17, 18, 19, and 20 which make contact between their respective pairs of fixed contacts when in normal or reverse positions respectively. This lever SML operates a tappet bar 21 which extends to the mechanical interlocking panel of the interlocking machine to mechanically interlock the lever SML with the other levers of the system in the usual way. The lever SML has four positions, namely, normal and reverse positions 1 and 4, and normal and reverse indicating positions 2 and 3 respectively. These positions are determined by the usual indication latch mechanism which has been diagrammatically illustrated as having an indication magnet IM which operates a locking member 22 sliding in a slot 23 in the lever and a locking member 24 for engaging the projection 29 on

the lever, all of which is to illustrate the features of a suitable mechanism such as disclosed, for example, in the patent to W. K. Howe, Patent No. 1,846,724, dated February 23, 1932.

Associated with the lever is a suitable locking magnet LM which is controlled in accordance with suitable detector locking, approach locking and the like in accordance with the usual interlocking practices which need not be explained in accordance with the present disclosure for an understanding of the features of the present invention. This lock magnet LM operates a lock bar 30 which engages a projection 35 on the lever in the usual way.

Associated with the indication magnet IM is a 15 magnet relay MR of the neutral slow acting type.

The position of the track switch TS is indicated in the tower by a switch position repeating relay WP which is of the usual polar neutral type.

Power is supplied for the control of the switch machine as well as its operation from a suitable battery source B. This battery supplies power to the interlocking machine over the buses 25 and 26 and to the various switch machines of the interlocking plant over the buses 27 and 28. It is of course to be understood that this battery B might be replaced by any suitable source such as a direct current generator or an alternating current generator, and also that suitable overload protection, terminal blocks and other devices employed in such interlocking plants are also preferably provided in an actual installation although omitted for the sake of simplicity in the present disclosure.

It is believed that the nature of the invention, 35 its advantages and characteristic features can be best understood with further description being set forth from the standpoint of operation.

Operation

40

Under normal conditions, the switch machine control lever SML is in a full normal position 1 in correspondence with the normal position of the track switch TS. With such normal conditions established, the point detector contact 45 mechanism has its movable contacts 10, 11, 12 and 13 in normal extreme positions with the track switch TS in a normal position and locked by the switch machine SM.

This completes a normal energizing circuit for 50 the relay WP from the positive bus 27, through bus wire 34, wires 40 and 41, back contact 42 of contactor C, wires 43 and 44, movable contact 12 of point detector contact mechanism PD in a normal position, wire 29, windings of relay WP, wire 38, movable contact 13 of point detector contact mechanism PD in a normal position, wires 46, 47, and 48, back contact 49 of reverse contactor RC, wire 50, back contact 51 of normal contactor NC, wire 52, bus wire 32, to the 60 negative bus 28. The energy, which flows in this normal energizing circuit for the relay WP, causes its neutral contacts to be actuated to energized positions and its polar contacts to be actuated 65 to right hand normal positions. Under such circumstances, the signal control circuits which can be properly completed with the track switch TS in a normal position may be closed, if desired, as the movable contact 20 of the lever SML is in 70 a normal position in correspondence with the polar contact 53 of relay WP and the neutral contact 54 of relay WP is picked up.

Normal to reverse operation.—Let us assume 75 that the operator desires to operate the track

switch TS from its normal locked position to its reverse locked position. To do this, he actuates a lever latch (not shown) which closes a contact (not shown) allowing the lock magnet LM to be energized providing the approach locking and detector locking is in condition to allow safe operation of the track switch. The energization of the lock magnet LM causes the locking member 30 to be picked up so that the lever SML may be freely moved to the reverse indicating position 3.

The indication magnet IM is deenergized allowing the locking member 22 of the indication latch mechanism to freely drop into the lower portion 15 of the slot 23, and the locking member 24 remains in a lowered position to avoid the detent 29.

However, the reverse movement of the lever SML is stopped at position 3 by reason of the locking member 22 of the indication latch mechanism.

20 Also, the tappet bar 21 is operated to a mid stroke position in which the conflicting levers are prevented from operation by mechanical locking.

With the lever SML in the position 3, the signal control circuits are broken as the movable contact member 28 is out of correspondence with the polar contact 53 of the relay WP.

With the movable contact member 16 in the position 3, the reverse contactor relay RC at the track switch location is energized by a circuit closed from the positive bus 27, through bus wire 31, wire 55, back contact 56 of contactor C, wires 57 and 58, movable contact 10 of point detector contact mechanism PD in a normal position, wire 59, windings of reverse contactor RC, wire 60, back contact 61 of normal contactor NC, wire 62, back contact 63 of overload device OL, line wire 33, jumper wire 64, contacts 65-16, wire 66, to the negative bus wire 26.

40 The response of the reverse contactor RC opens the normal energizing circuit for the relay WP at its back contact 49 and closes a shunt circuit for the relay WP at its front contact 49. This shunt circuit for the relay WP is closed from its right hand terminal, through line wire 30, movable contact 13 of point detector contact mechanism PD in a normal position, wires 46, 47, and 48, front contact 49 of reverse contactor RC, wire 48, movable contact 12 of point detector contact mechanism PD in a normal position, line wire 29 to the left hand terminal of the relay WP.

This opening of the normal energizing circuit of the relay WP and the shunting of its windings causes its neutral contacts to drop away, 55 thereby indicating the equivalent of the unlocked condition of the track switch TS although up to this time no operation thereof has occurred.

The deenergization of the relay WP and the closure of its back contact 69 allows energizing 60 current to be applied to the contactor C which then completes the operating circuit of the switch machine motor including the armature and field windings A and F.

This reverse energizing circuit for the contactor C is closed from the positive bus wire 25, wire 68, back contact 69 of relay WP, wire 70, contacts 71-77, jumper wire 72, line wire 34, back contact 73 of overload device OL, wire 74, front contact 75 of reverse contactor RC, wires 70 76 and 77, windings of contactor C, wire 78, bus wire 32, to the negative bus 28.

This energization of the contactor C completes the reverse operating circuit for the switch machine motor from the positive bus 27, through bus wire 31, wires 80 and 81, front contact 82 of

reverse contactor RC, wire 83, field windings F, wire 84, overload coil 15 of the overload device OL, wire 85, back contact 86 of normal contactor NC, wire 87, front contact 88 of contactor C, armature winding A, wire 89, bus wire 32, to the negative bus 28. This energization of the armature and field windings A and F causes the unlocking of the track switch TS and its operation to a reverse extreme locked position.

It is to be noted that this picking up of the contactor C connects the reverse contactor RC across the control line wires 33 and 34, as the front contact 56 of the contactor C is now closed. This circuit is closed from wire 34, through the back contact 73 of overload device OL, wires 74 15 and 90, front contact 91 of reverse contactor RC, wires 92 and 93, front contact 56 of contactor C, wires 57 and 58, movable contact 10 of point detector contact mechanism PD in normal and mid stroke positions, wire 59, winding of reverse contactor RC, wire 60, back contact 61 of normal contactor NC, wire 62, back contact 63 of overload device OL to wire 33. This means that the reverse contactor RC is now subject to energization through its stick circuit including its own 20 front contact 91 and the line wires 33 and 34. It should be noted that contact 56 is preferably a make-before-break contact so that the reverse contactor RC will not be momentarily deenergized upon the shift of this contact to a picked 30 up position.

As soon as the contactor C is picked up, the circuit for relay WP is further opened at back contact 42 and a second shunting circuit is completed for the relay WP from its right hand terminal through line wire 30, movable contact 13 of point detector contact mechanism PD in a normal position, wires 46 and 47, front contact 42 of contactor C, wires 43 and 44, movable contact 12 of point detector contact mechanism PD in a normal position, line wire 29, to the left hand terminal of relay WP.

Also, at the time the track switch TS is unlocked, the contacts 10, 11, 12, and 13 of the point detector contact mechanism PD are moved to mid-stroke positions. The energizing circuit for the contactor NC or RC is not broken by such movement, as the contacts 10 and 11 maintain their respective circuits closed in moving in the proper direction toward their mid-stroke positions, in such a manner that both their respective circuits are closed in the mid stroke position. This is diagrammatically illustrated by the jumpers 94 and 95. With the movable contacts 12 and 13 in mid stroke positions, a shunt circuit 55 is completed for the relay WP by connecting the wires 29 and 30 through the jumper 130.

Assuming that the proper operation of the track switch TS takes place, then at the end of the operating stroke, when the switch machine 60 SM has locked the track switch TS in an extreme reverse position, the movable contacts 10, 11, 12, and 13 of the point detector contact mechanism PD are operated from mid stroke to extreme reverse positions. Although the movable contacts 65 12 and 13 are in reverse positions, the relay WP thereby being unshunted insofar as the jumper 130 is concerned, another shunt circuit is completed until the contactor C assumes a deenergized position. This shunt circuit is closed from the wire 29, through movable contact 12 in a reverse position, wires 96 and 46, front contact 97 of contactor C, wires 98 and 99, movable contact 13 of point detector contact mechanism PD in a reverse position, to the wire 30.

Upon the movement of the contact 10 of the point detector contact mechanism PD to a reverse position, the stick circuit for the reverse contactor RC is opened and its contacts drop away and thereby deenergize the contactor C by 5 opening its circuit at front contact 75.

It is to be noted, that the deenergization of the contactor RC initially opens the energizing circuit of the switch machine motor at front contact 32, and then shunts the field winding F 10 from its lower terminal through wire 83, back contact 82 of contactor RC, wire 101, back contact 86 of contactor NC, wire 85, overload winding 15, wire 84, to the upper terminal of the field winding F. The deenergization of the contactor C shunts the armature A by the closure of its 15 back contact 33 through an obvious circuit. The short circuiting of both the field and armature windings accomplishes an appreciable dynamic snubbing effect for the switch machine mechanism to bring it quickly to rest.

As soon as the contactors RC and C are both deenergized, then the reverse energizing circuit is closed for the switch position indicating relay WP from the positive bus 21, through bus wire 25, wires 49 and 102, back contact 91 of contactor C, wires 98 and 99, movable contact 13 of point detector contact mechanism PD in a reverse position, wire 30, windings of relay WP, wire 28, movable contact 12 of point detector contact mechanism PD in a reverse position, wires 96, 46, 47, and 48, back contact 49 of contactor NC, RC, wire 52, back contact 51 of contactor NC, wire 52, bus wire 32, to the negative bus 28. This causes the polar contacts of the relay WP to be actuated to left hand reverse positions and 35 the neutral contacts of the relay WP to be actuated to picked up positions.

It is to be remembered that the lever SML was assumed to be operated from its normal position 1 40 to the reverse indicating position 3 from which it is to be operated to the full reverse position 4 upon the reception of an indication of the complete reverse operation of the track switch TS. Returning for a moment to the initial operation 45 of the lever to the position 3, an energizing circuit is closed for the magnet relay MR with the lever out of correspondence with the position of the track switch as indicated by the relay WP.

This reverse out of correspondence energizing 50 circuit for magnet relay MR is closed from the positive bus 27 through bus wire 25, wire 103, front contact 104 of relay WP, wire 105, polar contact 106 of relay WP in a right hand position, wires 107 and 108, contacts 109-19, wires 110 55 and 111, windings of magnet relay MR, wire 112, bus wire 26, to the negative bus 28. This circuit is closed only so long as the relay WP remains energized and is more particularly useful for the purpose of restoring the lever to its 60 full former position in the event that there fails to be a response in the control system sufficient to deenergize the relay WP which will be described in detail under the heading "If system 65 fails to respond".

Under the normal operation of the system as 70 assumed in the present case, the relay WP becomes de-energized upon the response of the contactor RC to the control lever and the closure of its back contact 104, thus effected, completes an energizing circuit for the magnet relay MR from the positive bus wire 25, wire 103, back contact 104 of relay WP, wires 113 and 114, windings of relay MR, wire 112 to negative bus wire 26. Thus,

the magnet relay MR is energized throughout the operation of the track switch TS.

Then, at the completion of the operation of the track switch TS, and upon the energization of the relay WP which actuates its polar contacts 5 to the left and its neutral contacts to picked up positions, the magnet relay MR is de-energized by the opening of back contact 104 so that after a predetermined time its contacts drop away, but before this predetermined time elapses, the 10 indication magnet IM is momentarily energized by a circuit closed from the positive bus 25, wire 103, front contact 104, wire 105, polar contact 106 of relay WP in a left hand position, wire 114, contacts 115-18, wire 116, windings of indication magnet IM, wire 117, front contact 118 of magnet relay MR, wire 119, to the negative bus 26. This momentary energization of the indication magnet IM actuates its locking member 22 to an unlocked position, so that the operator may operate the lever SML to a full reverse position 4, in correspondence with the position of the track switch TS.

Reverse to normal operation.—It is readily apparent that the operation of the track switch 25 TS from a reverse position to a normal position is merely an inverse function of the operation pointed out above, and therefore need not be explained in detail. However, it is considered expedient to point out the different circuits involved although the associated operation is not fully explained in connection therewith.

With the lever SML in the normal indicating position 2 and the track switch TS in a reverse position, the initial energizing circuit for the 35 normal contactor NC is closed from the positive bus 27, through bus wire 31, wire 55, back contact 56 of contactor C, wires 57 and 129, movable contact 11 of point detector mechanism PD in a reverse position, wire 120, windings of normal 40 contactor NC, wire 121, back contact 75 of reverse contactor RC, wire 74, back contact 73 of overload device OL, line wire 34, contacts 122-17, wires 123 and 65, to the negative bus 26.

The normal pick-up circuit for the contactor C 45 is closed from the positive bus wire 25, wire 68, back contact 69 of relay WP, wires 70 and 124, contacts 125-16, line wire 33, back contact 63 of overload device OL, wire 62, front contact 61 of contactor NC, wire 71, windings of contactor 50 C, wire 78, bus wire 32, to the negative bus 28.

The normal stick circuit for the normal contactor NC is closed from the positive bus wire 25, wire 68, back contact 69 of relay WP, wires 70 and 124, contacts 125-16, line wire 33, back 55 contact 63 of overload device OL, wires 62 and 126, front contact 127 of contactor NC, wires 128 and 93, front contact 56 of contactor C, wires 57 and 129, movable contact 11 of point detector contact mechanism PD in reverse and mid-stroke 60 positions, wire 120, windings of normal contactor NC, wire 121, back contact 75 of reverse contactor RC, wire 74, back contact 73 of overload device OL, line wire 34, contacts 122-17, wires 123 and 66, to the negative bus 26. When the point detector contact mechanism PD operates movable contact 11 to a mid-stroke position, the jumper wire 95 is considered as the equivalent of a sliding contact so that the normal stick circuit for the normal contactor NC is continued intact throughout the normal operation of the track switch TS.

The normal energizing circuit for the switch machine motor is closed from the positive bus 27, through bus wire 31, wire 89, front contact 86 of normal contactor NC, wire 85, overload 75

winding 15 of overload device OL, wire 84, field winding F, wire 83, back contact 82 of reverse contactor RC, wires 101 and 87, front contact 88 of contactor C, armature winding A, wire 89, bus wire 32, to the negative bus 28.

- With the normal contactor NC picked up and the contacts of the contactor C still de-energized, before the response of the movable contacts 12 and 13 of the point detector contact mechanism 10 PD, the circuit for relay WP is broken at back contact 51 and a shunt circuit is closed for the relay WP from wire 29, through movable contact 12 of point detector contact mechanism PD in a reverse position, wires 96, 46, 47, and 48, back contact 49 of reverse contactor RC, wire 50, front contact 51 of normal contactor NC, wire 99, movable contact 13 of point detector contact mechanism PD in a reverse position, to the wire 30.

With both the contactors NC and C picked up, 20 a shunt circuit is closed from the wire 29 through contact 12 of point detector contact mechanism PD in a reverse position, wires 96 and 46, front contact 97 of contactor C, wires 98 and 99, movable contact 13 of point detector contact mechanism PD in a reverse position to the wire 30.

During the operation of the track switch TS while it is unlocked, the movable contacts 12 and 13 are in mid-stroke positions so that the wires 29 and 30 are shunted by the jumper wire 30 130.

At the end of the normal operation, with the contactors NC and C energized but with the movable contacts 12 and 13 in normal positions a shunt circuit is closed from wire 29 through the 35 movable contact 12 of point detector contact mechanism PD in a normal position, wires 44 and 43, front contact 42 of contactor C, wires 47 and 46, movable contact 13 of point detector contact mechanism PD in a normal position, to wire 30. Thus the shunt circuit is maintained 40 closed until the normal energizing circuit for the relay WP (above described) is completed upon the dropping away of the contacts of the contactor C. In other words, the contactor C is 45 always the last to become picked up at the beginning of a cycle of operation and is always the last to be dropped at the end of a cycle of operation.

The normal out of correspondence energizing 50 circuit for the magnet relay MR is closed from the positive bus wire 25, wire 103, front contact 104 of relay WP, wire 105, polar contact 106 of relay WP in a left hand position, wires 114 and 131, contacts 132-19, wires 133, 110 and 111, 55 windings of magnet relay MR, wire 112, to the negative bus 26.

The normal energizing circuit for the indication magnet IM at the completion of the normal 60 operation is closed from the positive bus 25, wire 103, front contact 104 of relay WP, wire 105, polar contact 106 of relay WP in a right hand position, wire 107, contacts 134-18, wires 135 and 116, windings of indication magnet IM, wire 117, front contact 118 of magnet relay MR, wire 119, to 65 the negative bus 26.

Reversal in mid stroke.—When the track switch TS is in operation, the movable contacts 10 and 11 of the point detector contact mechanism PD are in midstroke positions, so that either one of 70 the contactors NC or RC may be picked up to cause the opposite operation of the switch machine. However, these contactors are interlocked in such a manner that each is picked up through a back contact of the other so that only 75 one may be picked up at any one time. If a

particular contactor is picked up and energized through its stick circuit which is completed during operation of the track switch, and the lever SML is moved to an opposite governing position, the direction of current flow in the windings of this contactor is reversed so that the magnetic flux in its winding is reduced to substantially zero and its contacts are dropped away. As soon as the contacts of that contactor drop away, the opposite contactor may be energized in accordance with the new position of the lever SML. 10

For example, assuming that the reverse contactor RC is maintained energized through its stick circuit during the reverse operation of the track switch TS, it is apparent that the current 15 is flowing from left to right in its windings; but if the lever SML is moved to a normal governing position 2, then the direction of current flow in the windings of the contactor RC is reversed so that its contacts drop away. This allows the 20 normal contactor NC to be energized through back contact 75.

During such a reversing operation, the contactor C will drop away due to its circuit being opened by front contact 61 or 75, and it must 25 drop away before the opposite one of the contactors NC or RC can be picked up as their pick-up circuits include back contact 56.

While the track switch TS is in operation, the relay WP is de-energized for reasons above 30 pointed out so that irrespective of the movement of the lever SML from one governing position to the other, the magnet relay MR is energized by reason of back contact 104 so that upon the completion of the operation of the switch into cor- 35 respondence with the lever, the indication magnet IM is energized allowing the final movement of the lever to unlock the mechanical locking.

Operation in the event of overload.—It is apparent that the overload winding 15 of the overload device OL is included in series with the field winding F of the series motor circuit, so that in the event of an occurrence of an overload thereby causing an abnormal current flow above a predetermined value, the contacts 63 and 73 of the 45 overload device OL are operated to picked up positions. When the front contact 63 of the overload device OL is closed, the stick winding 14 is connected across the wires 33 and 34 thus energizing the winding 14 with a polarity depending 50 upon the position of the lever SML. This polarity of energization is in correspondence with the polarity of energization as produced in the overload winding 15 for that operation, so that the contacts 63 and 73 are maintained in picked 55 up positions. The contact 63 is preferably of the make-before-break type, so as to insure that its contacts are picked up once the overload coil 15 has been effective to initially cause its actuation.

The stick winding 14 is maintained energized 60 until the lever SML is operated to an opposite position, at which time the energization of its winding in the opposite direction reduces the magnetic flux in the overload device OL to substantially zero so that its contacts drop away 65 breaking its stick circuit at front contact 63 so that its contacts remain in dropped away positions. Thus, during an operation if the overload device OL is operated, its contacts remain operated until the lever SML is moved to the new 70 position. It is readily apparent that the operation of the contacts 63 and 73 to picked up positions opens the pick-up and stick circuits for the contactors NC or RC so that they drop and open the motor circuit. 75

In the event that it is desired to provide some means associated with the overload winding 15 to prevent a temporary surge from operating the overload device OL as distinguished from a regular overload, suitable means as disclosed in the patent to Hoppe et al., Patent No. 1,877,876 dated September 20, 1932, may be employed.

If the system fails to respond.—The system of the present invention provides that the lever 10 SML may be returned to a full normal or reverse position from which it has been operated to the opposite half operating position providing there has been no response to unlock the track switch TS.

15 For example, if the operator moves the lever SML from a full normal position 1 to the reverse indicating position 3, and for some reason, such as a broken line wire 33 or 34, the switch TS fails to respond and the relay WP remains energized, 20 the operator may return the lever SML to the normal indicating position 2 and receive an energization of the indication magnet IM to return the lever to the full normal position 1.

This may be accomplished because the magnet 25 relay MR is energized by an out of correspondence circuit, previously described, with the lever SML in the position 3. Thus, upon the return of the lever SML to the position 2, the relay MR is picked up so that an energizing circuit for the 30 indication magnet IM is immediately closed. The relay MR is sufficiently slow acting to allow such operation, which is of course possible both for normal and reverse movements of the lever.

This return of the lever under such conditions 35 has heretofore been unknown as there has been no way of distinguishing between a situation where the relay WP remained energized in spite of lever operation or where the relay WP became energized at the end of a lever operation. In 40 the present system, the de-energization of the relay WP not only indicates the operation of the track switch TS but the anticipated operation of the track switch so that at any time that the relay WP is energized it is perfectly safe to release the lever to operate it to a full position 45 in correspondence with the direction of energization of the WP relay. These features may perhaps be best understood by considering the various conditions under which levers of the four-position type may possibly be juggled out of correspondence with their track switches which they 50 control.

Lever juggling.—Heretofore there have been two points in the cycle of operation of a track 55 switch employing the so called battery or constant current type of indication at which the lever could be juggled out of correspondence with its track switch. These two positions have been at the beginning and the end of the cycle of 60 operation.

At the beginning of a cycle of operation of a track switch, the difficulty arose that the lever could be moved to a new governing position giving the switch machine a temporary application 65 of energy and immediately returning the lever to the former governing position before its indicating relay WP would become de-energized, and thereupon receiving an energization of its indication magnet to return the lever to a full former 70 position. The lever thus returned to a full former position, would unlock the associated mechanical interlocking and allow signals to be cleared although the switch machine may have, upon the temporary application of power, unlocked the track switch and failed to return to a 75

corresponding full former position upon the return of the lever SML to the full former position.

The present invention obviates such a condition by providing that the indication relay WP 5 shall be de-energized before power shall be applied to the track switch operating mechanism. Thus, if the lever is moved to a new governing position and returned prior to the de-energization of the relay WP, it is perfectly safe to 10 actuate the indication magnet as there has been no application of power to the switch machine. If the relay WP has been de-energized at the beginning of the operation and has applied power to operate the switch machine and the lever is 15 returned to its former governing position, all of the contact mechanisms at the switch machine and the point detector contact mechanism must be in correspondence with the new governing position of the lever, with the motor de-energized, 20 in order to again energize the relay WP in correspondence with the lever to thereby receive an indication. In other words, it is impossible with a system provided in accordance with the present invention to operate the lever out of correspondence with the track switch at the beginning 25 of the operating stroke.

At the end of a cycle of operation of a track switch, the difficulty arose that a lever, instead of being left in its new governing position allowing the switch to fully complete its operation, 30 could be moved to its former position momentarily just prior to the locking up of the switch in the new position and then returned to the new governing position to receive an indication because the switch would have continued to operate to lock up momentarily and then be operated in the opposite direction toward its former position. If it happened that, due to the lever manipulation just cited, the switch became momentarily energized to operate toward its former position just enough to unlock the track switch and then failed to follow the change of the lever position to its new governing position, this would then leave the lever in the full position corresponding to its new governing position with 45 the track switch unlocked.

This sequence of events is not applicable to the system of the present invention, as a definite sequence of events in the operation of the track switch is in force wherein the indicating relay 50 WP is caused to anticipate, so to speak, the operation of the track switch so that it is always de-energized before the switch machine actually receives power.

In former types of systems where the indicating relay WP merely repeated the position of the track switch, it is apparent that the track switch would necessarily be unlocked and operated before such an indication could be given, and with this former type of arrangement the 60 undesired possibility of the failure of the switch to follow at the end of an operating cycle when the lever was quickly juggled was quite possible, but the present system eliminates this possibility.

Thus, the present system provides a sequence 65 of events in the control and indication of a track switch for the four-position type of interlocking lever wherein the full position of the lever cannot be attained unless the track switch is de-energized and in a corresponding extreme locked 70 position.

Modified form.—In Fig. 1A, is disclosed a form of the present invention employing the so called free lever embodied in the lever CL. Associated with this lever CL is a repeating relay WZ of the 75

polar-neutral type. The lever contacts 150 and 151 operated by the lever CL apply potential to the relay WZ in one direction or the other to cause the relay WZ to repeat the lever positions 5 and control the application of power to the switch machine by governing the line wires 33 and 34 in a similar manner as the lever contacts of the lever SML in Fig. 1. A lock relay L which is controlled in accordance with suitable approach and detector locking interrupts the control of the lever CL over the relay WZ so as to prevent further operation of the track switch under certain unsafe traffic conditions. In such cases, any control of the switch machine SM already initiated upon such interruption, is completed in spite of any lever movements to the contrary.

The switch position repeating relay WP is controlled in the same manner, as heretofore described, but the correspondence between the relay WP and the relay WZ is indicated by normal and reverse relays N and R which are interlocked through each other and which are suitably selected.

25 Although the illustration of Fig. 1A shows the lock relay L, the control relay WZ, the indicating relay WP and the signal circuit selecting relays N and R as located in the control tower, it is to be understood that any suitable disposition of the 30 apparatus may be made, and these devices and circuits may be located in the field if the wires 152 and 153 are made the line wires in place of the wires 33 and 34 for connecting the control tower and the field location. Irrespective of the particular disposition of the apparatus, the operation 35 remains the same in each case.

More specifically, the control lever CL when in the normal position illustrated energizes the control relay WZ through a circuit from the positive 40 bus 25, wire 157, lever contact 151 in a normal position, wire 153, front contact 155 of lock relay L, wire 161, windings of relay WZ, wire 160, front contact 154 of lock relay L, wire 152, lever contact 150 in a normal position, wire 156, to the negative 45 bus 26. Current flowing in this normal energizing circuit actuates the polar contacts of the relay WZ to right hand positions and its neutral contacts to picked up positions.

When the lever CL is operated to a reverse position, the direction of current flow in the relay WZ is reversed by reason of a circuit closed from the positive bus 25, through wires 157 and 159, control lever contact 150 in a reverse position, wire 152, front contact 154 of lock relay L, wire 160, windings of relay WZ, wire 161, front contact 155 of lock relay L, wire 153, control lever contact 151 in a reverse position, wire 158, to the negative bus 26. The current which flows in this 60 energizing circuit actuates the polar contacts of the relay WZ to lefthand positions and its neutral contacts to picked up positions.

The lock relay L is normally energized, so that the movement of the control lever CL is repeated by the relay WZ. The operation of the relay WZ 65 to a new position controls the corresponding apparatus at the field station over the line wires 33 and 34 as explained in connection with Fig. 1. In other words, the polar contacts 162 and 163 serve the same purpose as the contacts 65, 125, 70, 71, 122, 16 and 17 of Fig. 1 insofar as the reversal of polarity upon the line wires 33 and 34 is concerned. The back contact 164 of relay WP serves the same purpose as the back contact 69 of Fig. 1. Thus, it can be seen that the polar contact 153 75 of relay WZ serves to control the initial energiza-

tion of the contactors RC and NC; while the polar contact 162 is effective to control the energization of the contactor C following the deenergization of the relay WP and the closure of back contact 164 in response to the initial energization of the normal or reverse contactor NC or RC.

This arrangement provides that the same sequence of events occurs when the apparatus of Fig. 1A is employed in the tower as when the apparatus in Fig. 1 is employed in the tower.

When the track switch TS is in a normal position and locked as repeated by the relay WP, and the switch control relay WZ is in correspondence with the position of the track switch, a normal relay N is energized by reason of the circuit closed 15 from the positive bus 27, through wires 165 and 166, front contact 167 of relay WP, wire 168, polar contact 169 of relay WP in a right hand position, wire 170, windings of relay N, wire 171, back contact 172 of relay R, wire 173, polar contact 174 of 20 relay WZ in a right hand position, wire 175, front contact 176 of relay WZ, wires 177 and 178 to the negative bus 28.

On the other hand, with the track switch TS in a reverse position and locked as repeated by the 25 relay WP in correspondence with the relay WZ in a reverse position, the reverse relay R is closed by reason of a circuit from the positive bus 27, wires 165 and 166, front contact 167 of relay WP, wire 168, polar contact 169 of relay WP in a left hand 30 position, wire 180, back contact 181 of relay N, wire 182, windings of relay R, wire 183, polar contact 174 of relay WZ in a left hand position, wire 175, front contact 176 of relay WZ, wires 177 and 178, to the negative bus 28.

The energization of the normal relay N permits the signal control circuits to be selected in accordance with the normal position of the track switch TS; while the energization of the reverse relay R permits the signal control circuits to be selected 40 in accordance with the reverse position of the track switch. Only one of these relays N and R can be energized at a time because of the selection of each through a back contact of the other.

The signal control circuits are illustrated as including front contacts 184 of relay N, front contact 185 of relay R and back contact 186 of relay L. The signals cannot be cleared until the back contact 186 of relay L is closed, which occurs upon the actuation of the signal control lever to a clearing position. In other words, the initial actuation of the signal control lever (not shown) causes the locking up of the track switches included in the route to be cleared, and after such locking has occurred the signals may be cleared in accordance 50 with the route selected. Such a control for the lock relays has been illustrated in the pending application of Larry et al., Ser. No. 577,504, filed November 27, 1931. It is of course to be understood that any other suitable control may be employed in connection therewith such as shown for example, in the pending application of Dicke et al., Ser. No. 640,378 filed October 31, 1932.

Whenever the lock relay L is deenergized, the 65 relay WZ is maintained in its last actuated position by reason of stick circuits including back contacts 154 and 155 of lock relay L and polar contacts 187 and 188 of relay WZ. It is obvious that the polar contacts 187 and 188 can apply 70 energy to the windings of relay WZ of a polarity in accordance with their last actuated positions, as is well understood in the art. Although this stick type arrangement to maintain the relay WZ in an energized position has been illustrated, it is 75

to be understood that the polar contacts of the relay WZ are preferably of the stay-where-put type irrespective of the energization of the relay.

Summary.—The above description points out 5 the manner in which the interrelation between a switch indicating relay WP and the control of the switch is accomplished in such a manner that a predetermined sequence of events is required to thereby prevent the juggling of the control lever 10 out of correspondence with the switch which it controls irrespective of the quick manipulations which may be accomplished. This type of system in accordance with the present invention has been illustrated as adaptable both when the mechanical type of interlocking and the electrical 15 type of interlocking with free levers are employed.

In the later mentioned type of interlocking, it is of course understood that the control lever may be operated to an out-of-correspondence position 20 with the switch control relay WZ and the track switch TS while the track switch is locked, but this is immaterial to the selection of the signal control circuits as at that time the signal control circuits are actually established and the switch 25 is actually locked, so that any movement of the free control lever at that time is ineffective to cause any interruption of the signal control circuits then established.

If it is desired that the positioning of the switch 30 control levers, such as lever CL, for example, while the track switch is locked, be effective to operate the track switch subsequent to the unlocking of the track switch, and so related with the track switch as to prevent the clearing of an erroneous route under such conditions, the association of 35 the lock relay L with the signal control lever (not shown) and the interrelation of the control lever CL with the relay WP, can be accomplished as disclosed, for example, in the pending application of Dicke et al., Ser. No. 640,378, above mentioned.

The present invention provides the features of 40 positive action without the disadvantage of the locking up of the system in the event of a failure 45 of the track switch operating mechanisms to respond to operations in the mechanical type of interlocking systems to which the present invention has been shown as applied in Fig. 1.

Having described an interlocking system including either a free lever or a mechanical interlocked lever, as specific embodiments of the present invention, it is desired to be understood that 50 these forms are selected to facilitate in the disclosure of the invention rather than to limit the 55 number of forms which it may assume; and, it is to be further understood that various modifications, adaptations and alterations may be applied to the specific form shown to meet the requirements of practice, without in any manner 60 departing from the spirit or scope of the present invention except as limited by the appended claims.

What we claim is:

1. In an interlocking system for railroads, a 65 switch machine for operating a railroad track switch, a control device having normal and reverse positions, a normal contactor, a reverse contactor, a common contactor, point detector contacts controlled jointly by said switch machine 70 and said track switch, a switch position indicating relay, means for energizing said normal contactor only when said control device is in a normal position and said switch machine is in a reverse or mid stroke position, means for energizing 75 said reverse contactor only when said control

device is in a reverse position and said switch machine is in a normal or mid stroke position, means for energizing said switch position indicating relay in accordance with the position of said track switch as indicated by said point detector contacts only when said normal, reverse and common contactors are all deenergized, means for energizing said common contactor only when the particular normal or reverse contactor is energized in accordance with the position of said control device and said switch position indicating relay is deenergized, and normal and reverse operating circuits for said switch machine selected by said control means but closed only upon the energization of said common contactor. 15

2. In an interlocking system for railroads, a switch machine for operating a railroad track switch, a normal contactor, a reverse contactor, a common contactor, an indicating relay for indicating the position of said track switch only when 20 said normal, reverse and common contactors are deenergized, means for at times energizing either said normal or said reverse contactor thereby de-energizing said indicating relay, means energizing said common contactor only when one of said 25 normal and reverse contactors is energized and said indicating relay is deenergized, means causing operation of said switch machine to normal or reverse positions in accordance with said normal or reverse contactors respectively only when 30 said common contactor is energized, and traffic controlling circuits selected in accordance with the position of said track switch as indicated by said indicating relay.

3. In combination, a switch machine for operating a railroad track switch to normal and reverse extreme positions, control means capable of assuming normal, reverse and inactive positions, an indicating relay for indicating the normal or reverse positions of the track switch when 40 and only when said control means assumes an inactive position and at other times indicating an unlocked condition of the track switch, a common controller capable of being rendered active only when said control means is in a normal 45 and reverse position, and said indicating relay indicates an unlocked condition of the track switch, normal or reverse operating circuits for said switch machine selected by said control means in corresponding positions but closed only 50 if said common controller is being rendered active, and other circuits selected by said indicating relay.

4. In combination, a switch machine for operating a railroad track switch to normal and reverse positions, a control lever having normal and reverse positions, normal and reverse contactors at the switch machine, a common contactor at the switch machine, an indicating relay for indicating the normal, reverse or unlocked 60 condition of the track switch when all of said contactors are deenergized and for indicating an unlocked condition when any one or all of said contactors are energized, energizing means for said normal contactor effective when the track 65 switch is in a reverse or mid stroke position and said lever is in a normal position, energizing means for said reverse contactor effective when the track switch is in normal or mid stroke positions and said lever is in a reverse position, energizing means for said common contactor effective when said lever is in a normal or reverse position and the corresponding normal or reverse contactor is energized with said indicating 70 relay indicating the unlocked condition of the 75

track switch, normal or reverse operating circuits for said switch machine closed when the corresponding normal or reverse contactor is energized only if the common contactor is also energized, and circuits selected by said indicating relay only when a normal or reverse position of the track switch is indicated.

5. In combination, a switch machine for operating a railroad track switch to normal and reverse positions, a control lever having normal and reverse positions, normal and reverse contactors at the switch machine, a common contactor at the switch machine, an indicating relay for indicating the normal, reverse or unlocked condition of the track switch when all of said contactors are deenergized and for indicating an unlocked condition when any one or all of said contactors are energized, energizing means for said normal contactor effective when the 10 track switch is in a reverse or mid stroke position and said lever is in a normal position, energizing means for said reverse contactor effective when the track switch is in normal or mid stroke positions and said lever is in a reverse position, energizing means for said common contactor effective when said lever is in a normal or reverse position and the corresponding normal or reverse contactor is energized with said indicating relay indicating the unlocked condition of the track 15 switch, normal or reverse operating circuits for said switch machine closed when the corresponding normal or reverse contactor is energized only if the common contactor is also energized, a slow acting relay energized only when said indicating relay and said lever are out of corresponding normal or reverse positions or said indicating relay indicates the unlocked condition of the track switch, and means energized whenever said lever and said indicating relay assume corresponding 20 positions only while the contacts of said slow acting relay are still picked up.

6. In combination, a track switch, a switch machine for operating the track switch, a relay for distinctively indicating the position and locked condition of said track switch, a control lever for governing the operation of said track switch, an indication latch mechanism governing the operation of said lever, a slow acting relay, energizing means for said slow acting relay effective whenever said indicating relay indicates the switch to be unlocked and whenever said lever is out of its position corresponding to the locked position indicated by said indicating relay, and means for actuating said indication latch mechanism whenever said lever and said indicating relay are in corresponding positions only when the contacts of said slow acting relay are still picked up.

7. In combination; a track switch; a switch machine for operating said track switch; a control lever having normal and reverse full positions, and normal and reverse indication positions; an indication latch mechanism allowing the movement of said lever to a full position from the corresponding indication position only when released; a relay indicating the position and locked condition of said track switch and its correspondence with said control lever; means energizing said switch machine in accordance with the position of said lever only when said relay indicates a lack of correspondence between said lever and said track switch; and means for releasing said indication latch mechanism whenever said lever is in an indicating position corre-

sponding to the position and locked condition of said track switch as indicated by said relay.

8. In combination; a switch machine for operating a railroad track switch to normal and reverse positions; control means local to said switch machine for controlling its operation, said control means being capable of being pre-conditioned for normal or reverse control and capable of being subsequently rendered effective to accomplish a control operation of said switch machine in accordance with its pre-conditioning; a control lever remote from said switch machine; an indication relay associated with said lever for indicating the normal and reverse positions of said track switch and its unlocked condition whenever said track switch is actually unlocked or said control means is pre-conditioned for a new operation of said track switch; means for pre-conditioning said control means for normal or reverse control in accordance with said control lever; means for rendering said control means effective to accomplish a control operation of said switch machine only when said indication relay indicates the unlocked condition of said track switch; and means for controlling the movement of said control lever by said indication relay.

9. In combination, a track switch, a switch machine for operating said track switch, an indicating relay for distinctively indicating the position and locked condition of said track switch, a control lever for governing the operation of said track switch, an indication latch mechanism governing the operation of said lever, a slow acting relay, means controlled by said indicating relay either in a position for indicating the associated track switch unlocked or in a position for indicating the associated track switch locked out of correspondence with the associated lever for energizing said slow acting relay, means for actuating said indication latch mechanism whenever said lever and said indicating relay are in corresponding positions only when the contacts of said slow acting relay are picked up, and means controlled by said indicating relay for de-energizing said slow acting relay in response to the locking of said track switch in correspondence with said control lever.

10. In combination; a switch machine for operating a railroad track switch to normal and reverse extreme positions; control means capable of assuming normal, reverse and inactive positions; an indicating relay for at times indicating the normal and reverse positions of said track switch when and only when said control means assumes an inactive position and at other times indicating the unlocked condition of said track switch; a common controller capable of being rendered active only when said control means is in a normal or a reverse position and said indicating relay indicates an unlocked condition of said track switch; normal or reverse operating circuits for said switch machine selected by said control means in corresponding positions but closed only if said common controller is rendered active; and means controlled by said common controller in its inactive position for snubbing said switch machine.

11. In combination; a switch machine for operating a railroad track switch to normal and reverse positions; control means local to said switch machine for controlling its operation, said control means capable of being preconditioned for normal and reverse control and capable of being subsequently rendered effective to accomplish a control operation of said switch machine

in accordance with its preconditioning; a control lever remote from said switch machine; an indication relay associated with said lever capable of being energized to one position or another for indicating the normal and reverse positions of said track switch, said indication relay when deenergized indicating the actual unlocked condition of said track switch or the condition that said control means is preconditioned for a new operation of said track switch; means for preconditioning

5
10
tioning said control means for normal and reverse control in accordance with the position of said control lever; means for rendering said control means effective to accomplish a control operation of said switch machine only when said indication relay is deenergized; and means including said indication relay for controlling the movement of said control lever.
